MOORING FOR AIRSHIPS

Original Filed May 28, 1928 2 Sheets-Sheet 2

UNITED STATES PATENT OFFICE

FRANCIS HECTOR CLERGUE, OF MONTREAL, QUEBEC, CANADA

MOORING FOR AIRSHIPS

Original application filed May 28, 1928, Serial No. 281,066. Divided and this application filed April 4, 1929.
Serial No. 352,406.

My invention relates to moorings for airships, and is intended for use primarily in conjunction with mooring masts or like structures to which airships may be made fast and 5 about which the craft is free to swing so that its nose will keep pointing into the wind. The object of my invention is to provide a cradle structure or support movable (preferably upon circular rails) about the mast or 10 other point to which the aircraft is moored, so that the ship will be preserved from damage due to contact with the ground or to any wind force from any direction. In the preferred form of my invention, the cradle and 15 rail trolleys prevent not only downward movement of the ship, but upward and side- wise movement as well. The present application is a division of another application filed by me on May 28, 1928, Serial No. 20 281,066.

Without desiring to restrict myself to the specific details illustrated, I will now proceed to describe a satisfactory and preferred form of my invention, with reference to the 25 accompanying drawings, in which Fig. 1 is a plan view of a mooring and supporting arrangement embodying my invention; Fig. 2 is a vertical section on the line 2-2 of Fig. 1; Fig. 3 is a detail elevation of a portion of 30 the circular track along which the cradle is movable; and Fig. 4 is a vertical section on the line 4-4 of Fig. 3.

M designates a mooring mast of any well known or approved construction, generally 35 made with a rotating upper portion M' to which the nose Y' of the aircraft Y is adapted to be made fast, such portion M' being swiveled to swing about the vertical axis of the mast. Concentrically with the 40 mast I provide one or more cradle and trolley tracks, the example illustrated showing an inner track T and an outer track T', the distance between the tracks being equal to the radius of the inner track and being about 45 one third of the length of the airship to be

moored. Thus, for an airship 600 feet long, the inner track T would be 200 feet from the mast M, while the outer track T' would have a radius of 400 feet. But these circular tracks may be spaced apart any distances 50 best suited to the framing of the airship's structure.

The preferred track construction is as follows: At suitable intervals piers P of concrete or other suitable material are built 55 in the ground G, and through such piers extend vertical rods R on which are fitted clamps C adapted to be forced down by nuts N into tight engagement with one of the outside base flanges of an I-beam I forming one 60 of the rails of the track. The other or inner base flange of said I-beam is adapted to be held down by a clamp C' pivoted at C'' to a housing H secured to the pier P by tie rods R'. I prefer to have clamps C on every pier, 65 and clamps C' on every other pier. The clamp C' is adapted to be brought into active position by a wedge member W engaging a corresponding surface on said clamp and movable lengthwise on a rod A connected with the housing H. A nut or hand-wheel N', screwing on a threaded portion of 70 said rod A, serves to hold or release the wedge or holding member W and the clamp C'. In order to facilitate removal and replacement 75 of the beam I, the rod A, with the clamp mechanism W, N' thereon, is mounted to swing on the housing H about a horizontal axis A' ranging lengthwise of the track, and as the clamp proper C' is movable about the 80 axis C'' (which is parallel to A'), the entire clamping mechanism may be swung aside into a recess P' of the pier P, as indicated by dotted lines in Fig. 4. The housing H is provided with a seat H' in operative relation to 85 the clamp C', against which seat H' the wedge member W is adapted to abut in its operative position to prevent pivotal movement of the clamp C' and to lock said rod A against 90 swinging movements on the pivot A'. The 90

beam I may then be removed readily, after loosening the clamp C. The pier and clamp construction described is used alike for each of the rails. Fig. 3 shows an expansion joint 5 at the adjacent ends of beam sections I of the same rail. This joint consists of a fish plate F having longitudinal slots F' through which extend the shanks of bolts B carried by the end portions of the said beams I; nuts 10 and washers of the well-known type are fitted on said bolts, as indicated at B'.

The upper flanges of the I-beams constitute the tracks proper for the cradles. There is an outer cradle traveling on the outer track 15 T', and an inner cradle traveling on the track T. As these cradles are substantially alike, it will suffice to describe one of them in detail. The cradle comprises four trucks or trolleys D'' each having four upper rollers E and 20 four lower rollers G rotatable about transverse horizontal axes E' and G' respectively. The upper flanges of the track beam I fit between the upper rollers E and the lower rollers G, while the frame or body of the 25 trolley is of inverted U-shape and straddles the upper portion of the rail or beam I; thus the trolley is held against any substantial lateral movement as well as against any substantial upward or downward movement. 30 The several trolleys belonging to the same cradle are connected rigidly by a suitable frame X, the central portion of which is preferably made with a suitable platform to accommodate a motor truck bringing supplies, 35 mail, etc. for the airship, and on said platform I would also locate the controls of the adjusting mechanism shown and described in the original application of which this is a division. Of course the several trolleys 40 would be set at an angle to each other (in plan view), corresponding to the curvature of the track on which they run.

The lateral or outrigger portions X' of the cradle frame X, which like the cradle frame, 45 are supported by over and underslung trolleys, are connected with the lower ends of steadyng cables or stays V diverging upwardly, and the upper ends of these stays are connected with the hull at different levels. 50 It will be obvious that these cables or stays V should be detachable at least at one end, either at the ship or at the cradle frame.

It will be noted that the track rails project above the ground and are easily cleared of 55 snow, mud, etc. At suitable points I would arrange level crossings Z, which would also enable supply trucks, mail trucks, etc. to reach the clear space between the rails of the same track, which space would be made wide 60 enough (say, twelve feet) for trucks to travel readily between the rails of the same track T or T'. Inasmuch as the two cradles are independent of each other, they will adjust themselves properly to the respective portions of the airship.

I claim:

1. In a device of the class described, a track comprising rail-forming I-beams, supports permanently fixed adjacent to said I-beams, clamps engaging the bases of said beams at one side, and clamps movably mounted on said supports and movable toward and from said bases, adapted to engage them on the opposite side, and locking devices movably mounted on said supports and adjustable relatively thereto to lock said movable clamps in operative positions and to release the same. 70

2. In a device of the class described, a track comprising rail-forming I-beams, supports permanently fixed adjacent to said I-beams, clamps engaging the bases of said beams at one side, swinging clamps pivotally mounted on said supports and movable relatively thereto into and out of engagement with the other side of said bases, and means 80 adjustably mounted on said supports for tightening or releasing said swinging clamps. 85

3. In a device of the class described, a track rail having a base, a support permanently fixed adjacent to said rail-base, a fastening clamp pivotally mounted on said support adapted to engage said base, and a movable wedge adjustably mounted on said support and adapted to fix said clamp in its operative 90 position against pivotal movement, and adjustable to permit said clamp to be swung to an inoperative position relatively to said base. 95

4. A device for fastening track rails in place consisting of a stationary housing, a 100 clamp pivotally mounted on said housing, and a wedge member adjustably mounted on said housing and movable into engagement with said clamp to lock it against pivotal movement on said housing. 105

5. A device for fastening track rails in place consisting of a stationary housing, a seat on said housing, a clamp pivotally mounted on said housing in operative relation to said seat, a threaded rod pivotally mounted on said housing and arranged to extend between said clamp and seat, and a wedge member threaded on said rod and adjustable thereon for engagement with said seat and clamp to prevent pivotal movement 110 of the latter and said rod on said housing. 115

In testimony whereof I have hereunto set my hand.

FRANCIS HECTOR CLERGUE.
